(57) **CLAIM**

The ornamental design for an amusement game machine, as shown and described.

DESCRIPTION

FIG. 1 is a front elevation view of an amusement game machine, showing my new design in accordance with a first embodiment of the present invention;

FIG. 2 is a left side elevation view thereof;

FIG. 3 is a right side elevation view thereof;

FIG. 4 is a rear elevation view thereof;

FIG. 5 is a top view thereof;

FIG. 6 is a bottom view thereof; and,

FIG. 7 is a perspective view thereof.

The portions of the amusement game machine shown in broken lines form no part of the claimed design.
